UNITED STATES PATENT OFFICE.

HUGH W. SANFORD, OF KNOXVILLE, TENNESSEE.

RAILWAY CAR.

Application filed March 5, 1925. Serial No. 13,280.

To all whom it may concern:

Be it known that I, HUGH W. SANFORD, a citizen of the United States, residing at Knoxville, in the county of Knox and State of Tennessee, have invented a new and useful Improvement in Railway Cars, of which the following is a specification, reference being had to the accompanying drawing.

This invention relates particularly to such railway cars as are used in mines for hauling coal or ore.

The object of this invention is to produce a car of good construction and of large capacity for a given height above the rails, to the end that cars used in mines having low head room will have the largest feasible capacity for that head room.

In the accompanying drawings,

Fig. 1 is a side elevation of a car embodying my improvement, parts being in section;

Fig. 2 is an end elevation of the same car;

Fig. 3 is a plan of a little more than one-half of said car;

Fig. 4 is a bottom view of the part of the car shown by Fig. 3;

Fig. 5 is an upright transverse section on the line, 5—5, of Figs. 1, 3 and 4, looking toward the right;

Fig. 6 is an upright longitudinal section on the line, 6—6, of Figs. 3 and 4, looking in the direction of the arrow;

Fig. 7 is an upright longitudinal section on the line, 7—7, of Figs. 3 and 4;

Fig. 8 is a horizontal section on the line, 8—8, of Figs. 1 and 7;

Fig. 9 is an enlarged detail upright section on a part of the line, 5—5, of Figs. 1, 3 and 4, to more fully illustrate the axle and wheel structure;

Fig. 10 is a detail elevation showing a part of one of the axle bearings;

Figs. 11 and 12, illustrate details of one of the wheel hoods;

Fig. 13 is an upright, transverse section on the line, 13—13, of Fig. 6.

Referring to said drawings, A, A are side sills. These are of channel-form with an upper and a lower flange, A¹, and with circular apertures, A², to receive axle bearings, D.

B, B are end sill structures joined to the ends of the side sills, A. These end sill structures are similar to the end sill structure of my United States Patent, No. 1,486,547, dated March 11, 1924. The chief

feature of this structure is a plate metal end sill formed by shearing a suitable blank from a steel plate and bending the blank to form an upright web, B¹, and an upper flange, B², and a lower flange, B³, the flanges being used as a part of the coupling structure, as described in said Letters Patent. Each end of said plate metal member is secured to the adjacent ends of the adjacent side sills by means of an angle piece, B⁴, having one arm riveted or bolted to the web of the plate metal member and having its other arm lying in the channel of the side sill and riveted to the sill in the manner described in my said Letters Patent.

An I-beam, C, is placed midway between the side sills, A, and extended from the back face of one plate metal end sill member to the back face of the other of said members. At each side of the I-beam and at each end sill member is an angle member, C¹, having one arm riveted or bolted to the upright web of the plate metal member and having its other arm resting in the channel of the I-beam and similarly joined to the web of said beam. This I-beam is positioned to reinforce the end sill structures to adapt said structures to better resist pulling strains and impact strains. This I-beam may also be used as a part of the means for supporting the car floor or bottom.

These drawings have been made from drawings for a car for a 44-inch gage track, the car having a bottom width of 72 inches between the side sills, and the car body having a length of 10 feet, exclusive of the end sill and coupling structures.

In each aperture, A², in the side sills is seated an axle bearing, D, which surrounds one end of an axle, E. The bearing is cylindrical interiorly and exteriorly, and its outer end reaches through the adjacent aperture, A², and is integral with a base plate, D¹, which lies against the outer face of the web of the side sill and between the flanges, A¹, of said sill and is secured to said web by bolts or rivets, D². The end of the axle abuts against the inner face of said base plate. Next to the axle bearing, D, is the axle boxing, F, which closely surrounds the axle and has an annular flange, F¹, surrounding the adjacent end of the hub, G¹, of the wheel, G. The inner end of the bearing, D, has teeth, D³, which extend between corresponding teeth, F², on the axle boxing, F. By this means, these two members inter-

lock or inter-engage for holding the axle boxing against rotation. At the opposite end of the wheel hub, G¹, the axle is surrounded by another axle boxing, H, which has a flange, H¹, surrounding the adjacent end of the wheel hub. This axle boxing abuts against an annular shoulder, E¹, formed on the axle E. A set screw H², extends through the axle boxing, H, and bears against the axle for holding the axle boxing immovably on the axle. Whether the axle or the wheel will turn depends upon the ratio of friction when the car is on a straight track and on a curved track.

15 Each axle and its axle bearings and axle boxings together form an "axle structure".

The wheel hub, G¹, is provided with any suitable bearing. The drawings show anti-friction rollers, I, surrounding the axle 20 within the hub. This part of the construction may be of ordinary form. At each end of the hub a pair of washers, J, surround the axle and bear against the adjacent axle boxing and take end thrust and end 25 thrust wear and may be replaced. The axles, E, extend through apertures in the upright webs of the I-beams, C, those apertures being large enough to allow the passing of the annular flanges, E¹, of the axles.

30 The bottom, K, of the car occupies the spaces between the side sills, A, and the end sill structures, B, and the I-beam, C, preferably at the level of the lower edges of the side sills and the end sill structures and the 35 I-beam. The bottom is supported as will be described further on.

The side sills form parts of the side walls of the car body. On the upper flange of each side sill rests a side wall section, L, 40 which, in the form shown in the drawings, is wooden planking. Each such section is secured to the adjacent side sill by upright bars, L¹, lying against the outer face of said section and bent inward to lie against the outer face of the web of the adjacent side 45 sill. Said bars are secured to the section, L, and to the side sill by bolts or rivets, L².

50 Each end sill structure forms a part of the end wall of the car. Above each end sill structure is an end wall section, L³, having its outer face in the plane of the inner or back face of the plate metal end sill member. Angle members, L⁴, rest on the upper flange, B², of the plate metal end sill member and are riveted thereto. Bolts, L⁵, extend horizontally through said angle pieces and the wall section, L³, and adjacent upright bars, L⁶, which are applied to the inner faces of the end wall section and extend downward through apertures, K¹, in the bottom, K, and have their ends bent horizontally to form horizontal supporting arms, L⁷, bearing against the lower face of the bottom, K, and supporting said bottom. 60 A bolt, L⁸, extends through each arm, L⁷,

and the bottom, K, to secure the bottom and said arm firmly to each other.

The end wall section, L³, and the end sill structure together form the "end structure" of the car.

70 Each bottom plate has along the adjacent side sill an upward-directed flange K², which overlaps the inner face of the side sill. Along the I-beam, each bottom plate is offset upward to form a horizontal flange, K³, overlapping and resting on the adjacent lower flange of the I-beam. Each bottom plate is also shown supported from the axles, E, by hangers, K⁴, extending over the axles and downward and suitably secured 80 to the plate.

Because the bottom or floor, K, is below the axles, E, the wheels must extend downward through the bottom. Accordingly at each wheel, the bottom has an opening, K⁵, 85 large enough to receive the adjacent wheel and the axle boxings.

A hood, M, extends over the opening, K⁵, and the wheel and the axle boxings and the bearing, D. This hood consists of oblique 90 sides, M¹, having lower flanges, M², resting on the upper face of the adjacent bottom plate, K, and secured thereto by bolts, M³. The top, M⁴, of the hood is shown integral with the sides, M¹. The end of the hood 95 next the side wall has upturned flanges, M⁵, which bear against the outer upright saddle plate, M⁶, and are riveted to said plate. The lower part of the saddle plate, M⁶, is cut to seat on the bearing, D, and extend 100 downward at each side of the bearing to the bottom, K. Along the upper part of the bearing, D, the saddle plate is preferably provided with an inward turned flange, M⁷. At the opposite end of the hood there 105 is a similar inner upright end plate, M⁸, which has at its upper end a flange, M⁹, overlapping the end edges of the side and top of the hood and riveted thereto. The lower part of this end plate is cut out sufficiently to allow the plate to extend downward at each side of the adjacent axle boxing, H. 110

115 At each side of said opening, said plate is bent outward to form a flange, M¹⁰, resting on the bottom, K, and secured thereto by bolts, M¹¹. Along the upper part of the axle boxing, this end plate is bent away from the wheel to make a flange, M¹², resting like a saddle on the axle boxing. Thus the hood is given two saddle-like supports, 120 one on the axle bearing, D, and the other on the axle boxing, H.

125 The hood being thus supported, it is adapted to give support to the part of the bottom, K, to which the hood is attached. It has already been stated that the bottom is supported by the hangers, K⁴, reaching downward from the axles to the bottom; and that the ends of the bottom are supported by the arms, L⁷, of the upright bars, L⁶. 130

It has also been explained that the side edges of the bottom plates are turned upward to form flanges, K^2 and K^3 , the former overlapping and resting against the side sills and the other overlapping and resting on the lower flanges of the I-beams.

The several parts of the hood are to be assembled and joined to each other to make the hood complete, ready to be set into position and have its lower edges secured to the bottom, K , by means of the bolts, M^3 . It will be seen that this construction permits convenient detaching and removal of the hood.

15 The bearings, D , and the axles, E , are in a horizontal plane cutting the side sills. The parts of the plates, D^1 , which are opposite the ends of the axles form abutments to take end thrust from the axles.

20 I claim as my invention,

1. In a railway car of the kind described, the combination with side sills and an end structure, of a bottom plate and an upright bar supported by the end structure and having its lower end secured to the bottom plate for supporting the latter, substantially as described.

25 2. In a railway car of the kind described, the combination with side sills and an end structure, of a bottom plate and an upright bar supported by the end structure and having its lower end extending through and secured to the bottom plate for supporting the latter, substantially as described.

30 3. In a railway car of the kind described, the combination with side sills and an end structure, of a bottom plate having near its end an aperture, and an upright bar supported by the end structure and having its lower end reaching through said aperture and secured to the bottom plate for supporting the latter, substantially as described.

35 4. In a railway car of the kind described, the combination with side sills and an end structure and axles associated with the side sills, of a bottom plate extending below the axles, an upright bar supported by the end structure and having its lower end secured to the bottom plate for supporting the latter, and means intervening one of the axle structures and the bottom plate for supporting the latter, substantially as described.

40 5. In a railway car of the kind described, the combination with side sills and an end structure and axles associated with the side sills, of a bottom plate extending below the axles, an upright bar supported by the end structure and having its lower end secured to the bottom plate for supporting the latter, and means intervening one of the axles and the bottom plate for supporting the latter, substantially as described.

45 6. In a railway car of the kind described, the combination with side sills and an end structure and axles associated with the side

sills, of a bottom plate extending below the axles, an upright bar supported by the end structure and having its lower end secured to the bottom plate for supporting the latter, and means intervening one of the axles and its axle bearings on the one hand and the bottom plate on the other hand for supporting said plate, substantially as described.

7. In a railway car of the kind described, the combination with side sills and an end structure, of a bottom plate having an upward-directed side flange over-lapping the inner face of one of the side sills, and an upright bar supported by the end structure and having its lower end secured to the bottom plate for supporting the latter, substantially as described.

8. In a railway car of the kind described, the combination with a side sills and an end structure, of a bottom plate having an upward-directed side flange over-lapping the inner face of one of the side sills, and an upright bar supported by the end structure and having its lower end extending through and secured to the bottom plate for supporting the latter, substantially as described.

9. In a railway car of the kind described, the combination with side sills and an end structure, of a bottom plate having an upward-directed side flange over-lapping the inner face of one of the side sills and having near its end an aperture, and an upright bar secured to the end structure and having its lower end reaching through said aperture and secured to the bottom plate for supporting the latter, substantially as described.

10. In a railway car of the kind described, the combination with side sills and an end structure, of an axle structure, a bottom plate located below the axles and having one end supported at the adjacent end structure, and means supporting the bottom plate from one of the axles and one of the axle bearings, substantially as described.

11. In a railway car of the kind described, the combination with side sills and an end structure, of an axle structure, a bottom plate located below the axles and having one end supported at the adjacent end structure, and means supporting the bottom plate from one of the axles and one of the axle bearings and one of the axle boxings, substantially as described.

12. In a railway car of the kind described, the combination with side sills and end structures and axle structures, of a bottom plate below the axles, means joining one of the ends of said plate with one of the end structures, and a hood structure joined to the bottom plate and resting on one of the axle structures, whereby the bottom plate is supported, substantially as described.

13. In a railway car of the kind described,

- the combination with side sills and end structures and axle bearings and axles, of a bottom plate below the axles, means joining the ends of said plate with the end structures, hood structures joined to the bottom plate and resting on the axle bearing, whereby the bottom plate is supported, substantially as described.
14. In a railway car of the kind described, 10 the combination with side sills and end structures and axle bearings and axle boxings and axles, of a bottom plate below the axles, means joining the ends of said plate with the end structures, hood structures joined 15 to the bottom plate and resting on the axle bearing and the axle boxing, whereby the bottom plate is supported, substantially as described.
15. In a railway car of the kind described, 20 the combination with side sills and end structures and axles associated with the side sills and wheels on the axles, of a bottom plate extending below the axles and having openings for the wheels, and hoods in operative relation with one of the axles and with 25 the bottom plate to be supported by one of the axles and to support the bottom plate, substantially as described.
16. In a railway car of the kind described, 30 the combination with side sills and end structures and axles and wheels, of a bottom plate extending below the axles and having openings for the wheels, a hood extending over one of said openings and joined to the 35 bottom plate and having saddle flanges in operative relation with the adjacent axle for receiving support by said axle, substantially as described.
17. In a railway car of the kind described, 40 the combination with side sills and end structures and axles and wheels, of a bottom plate extending below the axles and having wheel openings, and a hood extending over one of said openings and being joined to said 45 bottom plate and having end plates in operative relation with the adjacent axle to rest upon and be supported by said axle, substantially as described.
18. In a railway car of the kind described, 50 the combination with side sills and end structures forming a quadrilateral frame, of a beam located between the side sills and having its ends secured to the end structures and having at each side of its lower part a lateral flange, and bottom plates supported 55 by said frame and having their inner side edges resting on said flanges, substantially as described.
19. In a railway car of the kind described, 60 the combination with side sills and end structures, of a beam located between the side sills and having its ends secured to the end structures and having at each side of its lower part a lateral flange, and bottom plates 65 having their ends secured to the end struc-
- tures and having their inner side edges resting on said flanges, substantially as described.
20. In a railway car of the kind described, 70 the combination with side sills and end structures, of a beam located between the side sills and having its ends secured to the end structures and having at each side of its lower part a lateral flange, axles extending through the beam and having their ends supported by the side sills, and bottom plates 75 below the axles and having their ends secured to the end structures and having their inner side edges resting on said flanges, substantially as described.
21. In a railway car of the kind described, 80 the combination with side sills and end structures forming a quadrilateral frame, of a beam located between the side sills and having its ends secured to the end structures and having at each side of its lower part a lateral flange, and bottom plates having their ends supported by said frame and having 85 their outer side edges upturned and overlapping the inner faces of the side sills and 90 having their inner side edges resting on said flanges, substantially as described.
22. In a railway car of the kind described, 95 the combination with side sills and an axle, of axle bearings supported on the side sills and surrounding the ends of the axle, wheels surrounding the axle, axle boxings each surrounding the axle and the adjacent wheel hub and said bearing and the adjacent axle 100 boxing having their meeting ends formed for inter-engagement whereby the axle boxing is held against rotation, substantially as described.
23. In a railway car of the kind described, 105 the combination with side sills and an axle, of axle bearings supported on the side sills and surrounding the ends of the axle, wheels surrounding the axle, axle boxings each surrounding the axle and the adjacent wheel hub and said bearing and the adjacent axle 110 boxing having inter-engaging teeth on their meeting ends whereby the axle boxing is held against rotation, substantially as described.
24. In a railway car of the kind described, 115 the combination with side sills and an axle having an annular flange, of axle bearings supported on the side sills and surrounding the ends of the axle, wheels surrounding the axle, outer axle boxings each surrounding 120 the axle and the adjacent wheel hub and said boxing and the adjacent axle boxing having their meeting ends formed for inter-engagement whereby the axle boxing is held against rotation, and an inner axle boxing 125 surrounding the axle between said annular flange and said hub, substantially as described.
25. In a railway car of the kind described, 130 the combination with side sills and end

- structures, of axles in a horizontal plane cutting the side sills, wheels on the axles between the side sills, a bottom extending under the axles, and hoods extending over the wheels, substantially as described.
26. In a railway car of the kind described, the combination with side sills and end structures, of bearings secured to the side sills in a horizontal plane cutting the side sills, axles in said bearings, wheels on the axles between the bearings, a bottom extending under the axles, and hoods extending over the wheels, substantially as described.
27. In a railway car of the kind described, the combination with side sills and end structures, of bearings secured to the side sills in a horizontal plane cutting the side sills and having end walls adapted to take axle end thrust, axles in said bearings, wheels on the axles between the bearings, a bottom extending under the axles, and hoods extending over the wheels, substantially as described.
28. In a railway car of the kind described, the combination with side sills and long end structures, end structure stiffening means located between the side sills, axles in a horizontal plane cutting the side sills, wheels on the axles between the side sills, a bottom extending below the axles, and hoods extending over the wheels, substantially as described.
29. In a railway car of the kind described, the combination with side sills and end structures, of axles in a horizontal plane cutting the side sills, wheels on the axles be-
- tween the side sills, and a bottom extending under the level of the axles, substantially as described.
30. In a railway car of the kind described, the combination with side sills and end structures, of axles in a horizontal plane cutting the side sills, wheels on the axles between the side sills, a bottom extending under the level of the axles, and hoods extending over the wheels, substantially as described.
31. In a railway car of the kind described, the combination with side sills and end structures, of bearings secured to the side sills and having their outer ends closed to form abutments for the end faces of the axles, axles in said bearings, wheels on the axles between the bearings, a bottom extending under the axles, and hoods extending over the wheels, substantially as described.
32. In a railway car of the kind described, the combination with side sills and end structures, of bearings extending through the side sills and having their outer ends closed to form abutments for the end faces of the axles, axles in said bearings, wheels on the axles between the bearings, a bottom extending under the axles, and hoods extending over the wheels, substantially as described.

In testimony whereof I have signed my name, this 18th day of February, in the year one thousand nine hundred and twenty-five.

HUGH W. SANFORD.

structures, of axles in a horizontal plane cutting the side sills, wheels on the axles between the side sills, a bottom extending under the axles, and hoods extending over the wheels, substantially as described.

26. In a railway car of the kind described, the combination with side sills and end structures, of bearings secured to the side sills in a horizontal plane cutting the side sills, axles in said bearings, wheels on the axles between the bearings, a bottom extending under the axles, and hoods extending over the wheels, substantially as described.

27. In a railway car of the kind described, the combination with side sills and end structures, of bearings secured to the side sills in a horizontal plane cutting the side sills and having end walls adapted to take axle end thrust, axles in said bearings, wheels on the axles between the bearings, a bottom extending under the axles, and hoods extending over the wheels, substantially as described.

28. In a railway car of the kind described, the combination with side sills and long end structures, end structure stiffening means located between the side sills, axles in a horizontal plane cutting the side sills, wheels on the axles between the side sills, a bottom extending below the axles, and hoods extending over the wheels, substantially as described.

29. In a railway car of the kind described, the combination with side sills and end structures, of axles in a horizontal plane cutting the side sills, wheels on the axles be-

tween the side sills, and a bottom extending under the level of the axles, substantially as described.

30. In a railway car of the kind described, the combination with side sills and end structures, of axles in a horizontal plane cutting the side sills, wheels on the axles between the side sills, a bottom extending under the level of the axles, and hoods extending over the wheels, substantially as described.

31. In a railway car of the kind described, the combination with side sills and end structures, of bearings secured to the side sills and having their outer ends closed to form abutments for the end faces of the axles, axles in said bearings, wheels on the axles between the bearings, a bottom extending under the axles, and hoods extending over the wheels, substantially as described.

32. In a railway car of the kind described, the combination with side sills and end structures, of bearings extending through the side sills and having their outer ends closed to form abutments for the end faces of the axles, axles in said bearings, wheels on the axles between the bearings, a bottom extending under the axles, and hoods extending over the wheels, substantially as described.

In testimony whereof I have signed my name, this 18th day of February, in the year one thousand nine hundred and twenty-five.

HUGH W. SANFORD.

DISCLAIMER.

1,569,037.—*Hugh W. Sanford, Knoxville, Tenn. RAILWAY CAR.* Patent dated January 12, 1926. Disclaimer filed July 19, 1926, by the patentee.

Hereby enters this disclaimer to that part of the claim in said specification which is in the following numbers and words, to wit:

“28. In a railway car of the kind described, the combination with side sills and long end structures, end structure stiffening means located between the side sills, axles in a horizontal plane cutting the side sills, wheels on the axles between the side sills, a bottom extending below the axles, and hoods extending over the wheels, substantially as described.

“29. In a railway car of the kind described, the combination with side sills and end structures, of axles in a horizontal plane cutting the side sills, wheels on the axles between the side sills, and a bottom extending under the level of the axles, substantially as described.

“30. In a railway car of the kind described, the combination with side sills and end structures, of axles in a horizontal plane cutting the side sills, wheels on the axles between the side sills, a bottom extending under the level of the axles, and hoods extending over the wheels, substantially as described.”
